(57) **CLAIM**

The ornamental design for an ice auger storage case, as shown and described.

DESCRIPTION

FIG. 1 is a side perspective view of an ice auger storage case, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a top view of the ice auger storage case, depicted in an open state.

The broken line showing of an interior lining is for the purpose of illustrating customizable foam inserts and forms no part of the claimed design.
